UNITED STATES PATENT OFFICE.

PETER I. LONGROD, OF EAST WILLIAMSON, NEW YORK, ASSIGNOR TO FRANK H. VAN EENWYK, OF EAST WILLIAMSON, NEW YORK.

CAN-FILLING MACHINE.

1,268,739.

Specification of Letters Patent.

Patented June 4, 1918.

Application filed March 18, 1916. Serial No. 84,506.

To all whom it may concern:

Be it known that I, PETER I. LONGROD, of East Williamson, in the county of Wayne and State of New York, have invented certain new and useful Improvements in Can-Filling Machines; and I do hereby declare the following to be a full, clear, and exact description of the same, reference being had to the accompanying drawings, forming a part of this specification, and to the reference-numerals marked thereon.

My invention relates to a machine for filling cans and the like and is adapted more particularly for use in connection with the canning of fruit and vegetables where it is desired to fill a maximum number of cans in a minimum amount of time.

The invention has for its main object to provide a simple and efficient semi-automatic machine of this class comprising an endless conveyer belt which automatically moves the cans through a carrier which is adapted for vibratory or oscillatory movement to settle and compact the contents of the cans received from a hopper located above the carrier. The invention also has for its object to provide improved means for closing the hopper discharge valve and for holding the cans in register with the hopper outlets, both of said means being preferably operative simultaneously by a manually controlled lever when a series of filled cans is to be replaced by another series of empty cans to be filled. To these and other ends the invention consists in certain improvements and combinations of parts all as will be hereinafter more fully described, the novel features being pointed out in the claims at the end of the specification.

In the drawings:

Figure 1 is a front elevation of a machine embodying my invention;

Fig. 2 is a sectional elevation taken on line *a—a* of Fig. 1;

Fig. 3 is a sectional elevation taken on line *b—b* of Fig. 1;

Fig. 4 is a top plan view of the machine;

Fig. 5 is a plan view of the hopper base with the hopper removed showing the gate for closing the discharge openings leading from the hopper, and

Fig. 6 is a sectional plan view taken on line *c—c* of Fig. 3.

Similar reference characters throughout the several views indicate the same parts.

Referring to the drawings by numerals, 1 represents a pair of transversely positioned frame supports connected centrally by a longitudinal member 2. Carried upon the frame supports 1 are upright frame members 3 and 4 connected at the front of the machine by a centrally disposed brace 5 and at the back by a correspondingly positioned brace 6. The top ends of the upright frame members 3 and 4 are beveled inwardly to receive the rails 7 which are inclined downwardly toward each other to engage the sloping sides of the hopper or container 8 as shown in Fig. 3. A receiving table 9 for supporting the cans or other receptacles is positioned at the right of the machine upon the frame members 4, the outer end of the table being supported by a pair of inclined braces 10 as shown in Figs. 1 and 2. At the left hand end of the machine is positioned a discharge table 11, the inner end of which is secured upon the frame members 3. The outer end of the discharge table is supported by the inclined braces 12 as shown in Fig. 1. Upon the outer end of the table 11 and braces 12 are provided bearings 13 in which a shaft 14 is journaled carrying a driving pulley 15 adapted to be driven by a belt 16 which may be connected with any suitable source of power. A pulley 17 is rigidly mounted upon the shaft 14 centrally of the table 11 as shown in Fig. 4. Secured upon the outer end of the table 9 and braces 10 are bearings 18 carrying a shaft 19 provided with a pulley 20. A belt 21 connects the pulleys 17 and 20 to form an endless conveyer for moving the cans 22 or other receptacles beneath the hopper or container 8. The tops of the tables 9 and 11 are recessed to receive the belt 21, the former being provided with a ledge 23 at the back side of the belt to form a stop or guide for the cans as they are carried along by the belt toward the hopper. Proper tension upon the belt is maintained by an idler 24 mounted on a shaft 25 journaled in arms 26 pivotally connected with the inner faces of the frame members 3 by suitable bolts 27 as shown in Figs. 1 and 3.

A movably mounted carrier 28 is provided for temporarily holding the cans while being filled and vibrated which preferably

comprises upper and lower walls 29 and 30 respectively connected by front and rear walls 31 and 32 respectively, as shown in Fig. 3. The carrier is pivotally suspended 5 at each end upon hangers 33 offset at 34 to extend to the inner faces of the frame members 3 and 4, upon which said hangers are pivotally mounted by suitable bolts 35. By suspending the carrier in this manner it 10 is free to be vibrated endwise beneath the hopper or container 8 which is adapted to rest within a recess formed in the upper face of the carrier top wall 29 as shown in Fig. 3. The wall 29 is provided with a plurality 15 of spaced openings 36 adapted to register with the cans 22 when the latter are in the position shown in Fig. 1. The conveyer or belt 21 is arranged to travel through the carrier 28, the ends of the latter being open 20 to receive and discharge the cans carried by the belt 21 from the receiving table 9 to the discharge table 11. The belt conveyer is adapted to travel upon the upper surface of the wall 30 of the carrier and between 25 the walls 31 and 32 thereof as shown in Fig. 3 to convey the cans or other receptacles beneath the openings 36 in the upper wall 29 of the carrier. In order to provide means for temporarily arresting the cans upon the 30 conveyer beneath said openings to fill the same from the hopper I position upon the inner face of the wall 32 upper and lower cleats 37 beveled at one end as indicated at 38 to assist in guiding the cans into position beneath the hopper. The cleats are provided with curved depressions 37^a corresponding substantially with the curvature of the cans and are so spaced as to cause the cans, when held therein, to register with 35 the openings 36 formed through the wall 29 of the carrier. A spring 39 is placed upon the side wall 31 of the carrier to engage and hold the first of the cans conveyed to the carrier by the belt 21. As each succeeding 40 can is brought into position by the belt conveyer it is halted by the can immediately ahead of it. When the cans are retained in these positions they are immediately in front of the depressions 37^a formed in the 45 cleats 37 as shown in Fig. 6. The spring 39 is of sufficient strength to hold the cans at rest upon the moving belt when said cans are empty, but will not hold them when they are filled with contents from the hopper. 50 It is therefore, necessary to provide means which may be moved into engagement with the cans while they are being filled and vibrated to compact the contents therein, otherwise the friction between the cans and 55 the belt due to the weight of said contents, would be sufficient to cause them to move with the belt against the action of the spring 39. It is also necessary to provide means for releasing the contents of the hopper 60 through the openings 36 into the cans regis- tering therewith and in this connection, I prefer to combine the means for carrying out these two operations in such a way that they will be performed simultaneously by the operation of a single member. To 70 this end I provide upon the carrier front wall 31 a bar 40 pivotally connected to said wall by means of suitable hinges 41, said wall being provided with an opening 42 to receive the bar as indicated in Fig. 3. 75 The inner face of the bar is provided with depressions 43 opposite the cans 22 as shown in Fig. 6. Next the depressions and spaced a slight distance therefrom is a can engaging member 45 extending the full length 80 of the bar 40 and engaging the latter at the points 46 as shown in Fig. 6. The can engaging member is preferably formed of spring material and is adapted to yieldingly engage the cans when forced into contact 85 therewith. Extending from the bar 40 centrally thereof is an arm 47, the outer end of which is pivotally connected with a link 48, the lower end of the link being pivotally connected with a tread 90 lever 49 pivoted at 50 to a bracket 51 mounted upon the longitudinal tie member 2 as shown in Fig. 3. The lever 49 is normally held in the position shown in full lines in this figure by a spring 52, one end of which 95 is secured to the brace 5 and the other end to the lever intermediate the pivot of the link 48 and bracket 51. The outer end of the lever is provided with a tread 53 adapted to be engaged by the foot of the operator 100 to depress the lever and thereby forwardly tilt the hinged can engaging member 40—45 to the position shown by dotted lines in Fig. 3 when it is desired to carry the empty cans beneath the openings 36 by the belt 21 and 105 to carry the filled cans to the table 11. As soon as the cans are in position to register with the openings, the lever is released and the spring 52 forces the elastic clamping member 45 into engagement with the cans 110 through the medium of the bar 40, arm 47 and link 48. The rear end of the lever is pivotally connected at 54 with a link 55, the upper end of which is pivotally connected 115 at 56 to the lower end of a lever 57 which is pivotally mounted upon a bolt 58 supported by a bracket 59 secured upon the bottom edge of the rear wall 32 of the carrier as shown in Fig. 3. The upper end of the lever 57 is pivoted upon a rod 60 120 which extends through the lever and projects a considerable distance upon the opposite sides thereof. The ends of the rod 60 are connected with bars 61 which are secured upon a horizontally arranged gate 125 62, which extends through the front wall 31 of the carrier immediately beneath the top wall 29 thereof. The ends of the gate are slidably mounted in guide members 63 positioned upon the front frame members 3 130

and 4, which are slotted at 64 to provide clearance for the ends of the gate when the latter is moved longitudinally of the machine upon vibration of the carrier 28. The gate 62 is also guided between the upper wall 29 and front wall 31 of the carrier as well as by the guides 63. The lever 57 at the point where it is pivoted upon the bolt 58 is provided with a vertical slot 65 to allow the lever to be slightly raised and lowered when it is being pivotally moved to operate the gate, thereby permitting the gate to move freely in a horizontal plane. The tread lever 49 is held against side movement by a pair of guide bars 66 terminating at their upper parts in upwardly diverging portions 67 each of which is secured to the brace 5 by suitable screws as shown in Fig. 1. Considerable play is allowed between the jaws at the lower ends of the links 48 and 55 and the tread lever 49 where they straddle the latter, to take care of the side movement of the links produced by the longitudinal movement of the vibrating carrier 28. The link 48 is provided with steadyng means comprising the oppositely positioned springs 68, the inner ends of which are secured to the link and the outer ends to the front frame members 3 and 4. The link 55 is provided with similar steadyng means comprising the springs 69, the inner ends of which are secured to the link and the outer ends to the rear frame members 3 and 4. The endwise vibration of the carrier 28 is effected by means of a pulley 70 mounted on a shaft 71 and driven by a belt 72. The shaft is mounted in bearings 73 on the frame members 4 and is provided with an eccentrically mounted disk 74, revoluble in a collar 75 carrying an extension 76 upon which is secured one end of a connecting rod 77, the other end of which is rigidly secured upon the bottom wall 30 of the carrier 28. A loose pulley 78 is mounted upon the shaft 71 and carries the belt 72 until it is desired to vibrate the carrier 28 at which time the belt is shifted to the fixed pulley 70 by a bar 79 suitably connected with the belt and slidably mounted on pins 80 carried by the frame members 4. The belt shifting bar is operated by a lever 81 with which it is pivotally connected at 82, the lower end of the lever being pivoted at 83 to one of the frame supports as indicated in Figs. 1 and 2. The vibration of the carrier 28 is effected by the means just described while the belt conveyer 21 is traveling through the carrier and without interfering with the movement of the belt upon the pulleys 17 and 20. The distance through which the carrier is moved longitudinally of the machine is very slight and is not sufficient to cause any undue strain upon the belt or deflection thereof.

The operation may be briefly summarized as follows: Prior to filling the hopper 8 with the vegetables or fruit to be canned, the driving belt 16 will be adjusted to stop the endless conveyer belt 21, and the operator adjusts the lever 81 to shift the belt 72 to the loose pulley 78 to prevent vibration of the can carrier 28, and the treadle lever 49 will be temporarily locked in the depressed dotted line position of Fig. 3, thereby moving the gate 62 rearward to close the hopper outlets 36, and also holding the can 75 clamping member 40-45 in the forwardly tilted dotted position. After the hopper is charged and the belt 21 is started, the empty cans are placed upon the belt at the table 9, and after four of the cans have been stopped 80 by the springs 39 and by contact with each other, in position for filling them, the operator will release the treadle lever 49 from its temporary lock (not shown) to allow the spring 52 to raise it to the full line position 85 and simultaneously the lever connections 55 to 61, will move the gate 62 frontwise to its full line position and thus open the hopper outlets 36 to allow the vegetables to flow from the hopper into the cans 22 while said 90 cans are held in the rear depressions 37a by the clamping member 40-45, which had been swung up rearward to thus act when the gate 62 was opened by the spring 52. During filling of the cans from the hopper the operator will pull the lever 81 to shift the belt 72 to the fast pulley 70, thereby rotating the shaft 71 and the cams 74 to cause the rod 77 to vibrate or oscillate the carrier 28 endwise to shake down and compact the 100 vegetables in the filled and clamped cans. When the cans are filled the lever 81 will be pushed to throw the belt 72 back to the loose pulley 78 to thereby stop the vibration of the carrier, and the operator now depresses the treadle 49 which simultaneously shifts the gate 62 rearward to close the hopper outlets 36, and tilts the can clamping member 40-45 frontwise to the dotted position and clear of the filled cans which now 110 are carried forward by the continuously moving belt 21 to the table 11, whence they are removed for sealing in any approved manner. As fast as one series of filled cans is released from the clamping member another series of empty cans now being carried forward by the belt 21 will be detained and clamped beneath the hopper outlets 36, to be filled as they are vibrated, and be then released and carried away to the table 11 by 120 the belt 21, as will readily be understood.

While I have shown and described certain detail forms of construction and arrangements of parts in connection with my improved can filling machine it is obvious 125 that the same may be varied to a considerable extent without departing from the spirit of the invention.

I claim as my invention:

1. A machine for filling receptacles com- 130

prising a carrier adapted to hold a plurality of receptacles, an endless conveyer running through the carrier adapted to deliver said receptacles to the latter and to discharge them therefrom, means for temporarily arresting the receptacles upon the carrier, means for filling the receptacles while held by the carrier and means for vibrating the carrier to compact the contents 10 of said receptacles.

2. A machine for filling receptacles comprising a carrier adapted to hold a plurality of receptacles, an endless conveyer adapted to deliver said receptacles to the carrier and to discharge them therefrom, means connected with the carrier for temporarily arresting said receptacles upon the conveyer, a hopper adapted to be charged with contents for filling the receptacles when 20 in said arrested position and means for releasing the contents of the hopper to discharge the same into the receptacles when the latter are held upon the conveyer.

3. A machine for filling receptacles comprising a carrier adapted to hold a receptacle, an endless conveyer adapted to deliver said receptacle to the carrier and to discharge the same therefrom, means connected with the carrier for temporarily arresting the receptacle upon the conveyer, a container above the carrier adapted to be charged with contents for filling the receptacle, a movable member normally closing the bottom of the container and means for operating said movable member to discharge the contents of the container into the receptacle.

4. A machine for filling receptacles com-

prising a carrier, an endless conveyer adapted to deliver a receptacle to the carrier and to discharge the same therefrom, means connected with the carrier for temporarily arresting the receptacle upon the conveyer, a container above the carrier adapted to be charged with contents for filling the receptacle, a movable member adapted to close the bottom of the container, means for operating said movable member to discharge the contents of the container into the receptacle while the latter is temporarily arrested upon the conveyer and means for vibrating the carrier to cause the vibration of the receptacle upon the conveyer for the purpose of compacting said contents within the receptacle.

5. A machine for filling receptacles comprising an endless conveyer adapted to carry a plurality of receptacles, a container adapted to be charged with contents for filling said receptacles and having a plurality of spaced openings at its bottom, a movable member adapted to close said openings, means operable to hold the receptacles upon the conveyer in registering engagement with said openings and a system of levers connected with said last mentioned means and said movable member adapted to be operated for simultaneously engaging the receptacles to hold them upon the conveyer and shifting said movable member to discharge the 70 contents of the container into the receptacles.

PETER I. LONGROD.
